UNITED STATES PATENT OFFICE.

JOHN J. WARREN, OF BROWNVILLE, NEW YORK.

APPARATUS FOR GRINDING WOOD PULP.

Application filed August 7, 1920. Serial No. 401,874.

To all whom it may concern:

Be it known that I, JOHN J. WARREN, a citizen of the United States, residing at Brownville, in the county of Jefferson, 5 State of New York, have invented certain new and useful Improvements in Apparatus for Grinding Wood Pulp; and I do hereby declare the following to be a full, clear, and exact description of the invention, 10 such as will enable others skilled in the art to which it appertains to make and use the same.

This invention relates to the grinding of wood into the so-called "mechanical" pulp 15 used in the manufacture of newsprint and other cheap papers. It is the object of the invention to make an improved grinder of the magazine type.

In order that the invention may be more 20 clearly understood reference is had to the accompanying drawings disclosing certain specific embodiments thereof, and in which;

Figure 1 is a transverse vertical section through the grinder, showing the relation of 25 the magazine, the grindstone and the feeder chains;

Fig. 2 is a vertical section taken along the axis of the grindstone;

Fig. 3 is a sectional detail showing apparatus used to cool the shaft of the grindstone;

Fig. 4 is a detail of the same apparatus taken on line 4-4 of Fig. 3;

Fig. 5 is a horizontal section on an enlarged scale taken on line 5-5 of Fig. 1, 35 and showing the chains and chain guides of the magazine;

Fig. 6 is a detail on an enlarged scale taken on line 6-6 of Fig. 5, and showing the chain mechanism and apparatus used 40 to bend the chain guides; and

Fig. 7 is a further detail of the feeder chain itself.

The magazine grinder shown in Figs. 1 and 2 comprises the ordinary cylindrical 45 grindstone 1 ordinarily electrically driven mounted upon shaft 2, journaled within bearings 3, and enclosed within housing 4. Below this grindstone is an outlet channel 5. The stone is securely fixed upon shaft 2 50 by means of bushings 6 and dished flanges

7 designed to hold the grindstone in place even though cracked. Mounted upon the grindstone, and supported by housing 4, is a preferably vertical magazine 8 terminating at its upper end in a hopper 11, into which 55 the wood to be ground is fed.

A positive and regulated feed of the wood within the magazine 8 is secured by means or two pairs of oppositely positioned endless chains 9, the inner strands or runs of 60 which move downwardly upon two opposite sides of the magazine. These sides are those which if extended would intersect the cylindrical face of the grindstone as clearly shown in Fig. 1. The specific manner in 65 which these chains are mounted within the side walls of the magazine will now be described.

The magazine itself comprises an outer metallic shell or casing 10 provided on its 70 interior with a lining of wooden blocks 12, the cross section of the magazine at its upper end being slightly greater than that at its lower end. Four vertical slots 13 are left in this wooden lining, in which are positioned 75 flexible channel irons 14 which serve as guideways for the inner runs of the feeder chains 9. These channels 14 are fixed near the lower end of the magazine, but at their upper ends are held by bolts passing 80 through slots within the channels, thus permitting free longitudinal movement the necessity for which will appear later. These channels 14 are tied together at suitable intervals by means of transverse tie plates 15 85 seated within horizontal slots 16 within the magazine lining, and normally bearing against the inner face of the metallic casing 10.

These channels 14 carrying the links of 90 chains 9 are so designed that they may be bent inwardly and thus force the chains into closer contact with the wood within the magazine. This bending or flexing is accomplished by means of a series of hand wheels 95 17 situated at intervals along the outer sides of the magazine, and shown in detail in Figs. 5 and 6. A series of pairs of horizontal channel irons 18 are fixed upon the outer sides of the casing 10. Upon the outer 100

flanges of these channel irons and in the planes of the chains are bolted plates 19 within which the hand wheels 17 are threadedly mounted. The inner ends of the 5 threaded shafts 20 of hand wheels 17 are seated within bearing members 22, which in turn bear upon the outer ends of compression springs 23. The other ends of these compression springs bear against plates 24 riveted to 10 tie plates 15, as shown in Fig. 6, or to the webs of channels 14 themselves. Apertures 25 are provided within the outer casing 10 at these points permitting springs 23 to enter and transmit pressure to channels 14. By 15 thus flexing these channels the effective width of the magazine can be varied at will and the pressure of the feed chains against the wood controlled.

Feeder chains 9 are made up of pairs of 20 heavy links 26 tied together by means of pins 27. These chains must be of unusually strong construction, as the total pressure which they exert upon the face of the grindstone amounts to between 45,000 and 25 60,000 pounds. Fixed on the inner face of each link 26, and near the lower or forward end thereof, is a spur or spike 28, the function of which is to bite into the wood and force it downwardly with the 30 chain. The position of these spikes or spurs is very important. If they were placed near the upper or rear ends of the downwardly moving chains they would tear and rip the wood as the chains moved away 35 and around their lower sprockets, and this would not only increase the required power, but would shorten the life of the chains. According to this invention, these spurs are fixed to the lower or forward ends of the 40 links. With this structure, as the chain leaves the wood and moves away around the lower sprockets, the link is pivoted at its upper end and the spur is, therefore, withdrawn from the wood in a direction substantially 45 along its length, and is consequently withdrawn as a nail is withdrawn from a board with great ease and no tearing or ripping of the wood.

Feeder chains 9 move around fixed lower 50 sprockets 29 and upper idler sprockets 30. Power is supplied to these chains from a variable speed motor 32 through the intermediary of a reducing worm gearing 33, 34 and 35. The speed of motor 32 is controlled 55 by an automatically operated rheostat on the field coils of the motor. These rheostats may be operated, for example, by a relay controlled by the current consumed by the grindstone, and the speed of motor 32 and 60 the movement of chains 9 may thus be made dependent upon the power consumption of the grindstone. Any speed-regulating means operated by the power consumed by the grindstone would suffice. There are 65 many such on the market, any one of which

could be used, and the mechanical details of which form no part of this invention. With a fixed, constant feed, the power consumption, when grinding small or loosely packed logs, would drop far below the 70 minimum required for efficiency, while with large, tightly wedged logs this consumption would probably rise above 1500 horsepower, and burn out the driving motor. With the regulatable feed of the invention, 75 however, the speed of the feed motor varies with the character of the wood being ground, and maintains the power consumption of the stone relatively constant.

It is common practice to supply the necessary water at the face of the grindstone with the attendant dangers disclosed above. According to this invention the water is introduced at the upper end of the magazine through pipe 36. This water is sprayed 80 over the wood in the upper part of the magazine and trickles down through the entire mass of pulpwood until it eventually reaches the stone. In so doing it not only thoroughly saturates this wood and thus softens and prepares it for grinding, but it itself is thoroughly pre-heated having come into intimate contact with the hot vapors rising from the grinding surfaces. This contact has not only resulted in pre-heating 85 the incoming water, but has condensed the outgoing vapors and thus conserved their heat content. The efficiencies gained by this simple expedient of introducing the water at the upper end of the magazine are 90 as important as the idea is simple. They may be briefly reviewed as follows: First, the water is pre-heated before coming into contact with the grindstone, and thus the danger of cracking is minimized; second, the wood 95 is thoroughly softened before grinding and may thus be ground with a minimum of power; and, third, the sensible heat otherwise lost by the passing off of the vapors generated by the grinding surfaces is 100 conserved.

In order to compensate for the inevitable wear of the grindstone, the lower end of the magazine is provided with an adjustable pocket. This pocket comprises a casting 115 37 supported upon housing 4 by means of threaded bolts 38 passing through apertured lugs 39, integral with the sides of the casting. This casting may be lowered by proper manipulation of nuts 40 to which access may be had by doors 42. In order to present a substantially continuous wall, the upper edges of the casting 37 and the lower edges of the magazine proper are provided with a series of interfitting fingers 43 and 44 respectively, although other means may 120 be employed.

The frictional heat of grinding is conducted through shaft 2 to bearings 3, and often results in melting the bearing metals 125

thereof, as stated above. In order to prevent this and to reduce the temperature of the shaft where it is journaled within the bearing metals, a cooling apparatus has been 5 devised according to this invention, and is clearly shown in Figs. 3 and 4. This apparatus comprises a pair of flanged collars 45 fixed upon the shaft 2 between the flanges 7 and bearings 3, the upstanding flanges of 10 which are spaced apart to permit the introduction of a cooling fluid between them. Surrounding the shaft at these points, one on each side of the grindstone, but not contacting therewith, are two housings 46. In 15 the upper halves of these housings are water chambers 47, the lower walls of which are provided with a series of small openings 48 through which water plays upon shaft 2 in the space between the collars 45. Water is 20 constantly supplied to these chambers 47 through water pipes 49. The water flows around shaft 2 and into the lower half of the housing 46, from which it flows away through aperture 50. In this manner heat 25 conducted from the grindstone along the shaft is absorbed by the water and carried off, and this heat cannot be added to the normal heat generated within the journal boxes themselves.

30 The operation of the method and apparatus described above may be briefly reviewed as follows: Magazine 8 is filled with the ordinary logs which are to be ground into paper pulp; water is sprayed on these logs through 35 pipe 36, and feed chains 8 are set in motion. Spurs 9 of these chains grip the logs along the entire length of the magazine and force them against the rotating grindstone. This force is sufficient to cause the entire column 40 to move slowly into grinding contact with the stone and entirely overcome any tendency of the logs to arch. The grip which these chains have upon the wood may be illustrated by reversing their movement.

45 Upon doing this it has been found that the entire column may be moved upwardly, none of the central logs dropping out. The fact that the lower end of the magazine is slightly smaller than the upper tends to increase the 50 grip of the chains upon the wood as the latter descends and is usually sufficient for all purposes. It sometimes happens, however, when logs of varying shapes and sizes are being ground that they are loosely 55 packed, and hence additional pressure should be brought to bear upon them to consolidate the column. This may be readily effected by screwing inwardly hand wheels 17, which results in bending or flexing the chain guides 60 14, and pressing the chains even more tightly against the wood. Meanwhile the water through pipe 36 is softening the logs and becoming pre-heated. As the grindstone wears the pocket at the lower end of the magazine 65 is extended.

With this apparatus it is never possible for the stone to race free of any load, nor be subjected to greater grinding pressure than it can well stand, for the variable speed motor 32 controls the rate of feed and maintains 70 it as nearly uniform as is mechanically possible.

Many of the features of my invention shown and described in this application are not claimed herein, but are being claimed in 75 my copending application, Serial No. 594,501, filed October 14, 1922, which is a continuation in part of the present case.

I claim:

1. A wood-pulp grinder of the magazine 80 type comprising the combination of a grindstone, a magazine adjacent to the grindstone and adapted to receive the wood to be ground, endless feed chains operating in the magazine for positively feeding the wood to 85 the grindstone, flexible channels or guide ways in the inner walls of the magazine in which the feed chains move, and means for flexing these channels to vary the effective 90 width of the magazine.

2. A wood-pulp grinder of the magazine type comprising the combination of a grindstone, a magazine adjacent the grindstone adapted to receive the wood to be ground, 95 flexible channels or guide ways in the inner walls of the magazine in which feed chains move, and means for flexing these channels to vary the pressure exerted by the chains upon the wood.

3. A wood-pulp grinder of the magazine 100 type comprising the combination of a grindstone, a magazine adjacent thereto adapted to receive the wood to be ground, an adjustable pocket at the lower end of the magazine adapted to be lowered as the grindstone 105 wears away, downwardly extending fingers on the magazine proper, and upwardly extending fingers on the adjustable pocket, the two sets of fingers arranged to interfit and thus maintain a substantially unbroken wall 110 when the pocket is lowered.

4. A wood-pulp grinder of the magazine type comprising the combination of a grindstone, a magazine adjacent to the grindstone adapted to receive the wood to be ground, a lining in the magazine, vertical slots in the lining, flexible channels or guide ways in the slots, endless feed chains operating within the magazine for positively feeding the wood to the grindstone and held within 115 the channels or guide ways, and means for flexing these channels to vary the pressure exerted by the chains upon the wood.

5. A wood-pulp grinder of the magazine type comprising the combination of a grindstone, a magazine adjacent to the grindstone adapted to receive the wood to be ground, endless feed chains operating within the magazine for positively feeding the wood 125 to the grindstone, and means for varying 130

the effective width of the magazine to control the pressure of the feed chains against the wood.

6. A wood-pulp grinder of the magazine type comprising the combination of a grindstone, a magazine adjacent thereto adapted to receive the wood to be ground, and an ad-

justable pocket at the lower end of the magazine adapted to be lowered as the grindstone wears away, the corresponding inner faces 10 of the magazine and pocket being substantially in the same plane.

In testimony whereof I affix my signature.

JOHN J. WARREN.
